UNITED STATES PATENT OFFICE.

PATRICK B. DELANY, OF SOUTH ORANGE, NEW JERSEY, ASSIGNOR TO THE TELEPOST COMPANY, OF NEW YORK, N. Y., A CORPORATION OF MAINE.

TELEGRAPHY.

1,146,752.

Specification of Letters Patent. Patented July 13, 1915.

Application filed December 29, 1908. Serial No. 469,804.

To all whom it may concern:

Be it known that I, PATRICK B. DELANY, a citizen of the United States of America, residing in South Orange, in the county of 5 Essex, State of New Jersey, have invented certain Improvements in Telegraphy, of which the following is a specification.

My improvement contemplates primarily the increase of speed of transmission by the 10 use of a perforated tape and automatic transmission of signals over the line, the reproduction of the signals in perforations at the receiving station, and the use of the reproduced tape for automatic transmission in 15 a local sounder circuit, for transcription by sound at a speed under control of the operator.

One hundred and twenty-five words per minute can be perforated at a receiving station 20 and the tapes distributed among five operators, each having a local transmitter circuit with a sounder into which the signals perforated in his tape are transmitted and reproduced on the sounder and, by the operator, transcribed by the use of a typewriting machine or otherwise.

As this system can be duplexed the equivalent of ten first class Morse circuits can be realized over a single wire wherever a 30 polar duplex will operate.

An important advantage of this system lies in the fact that the signals produced in the local reading circuit are firm and uniform, being in no way affected by line conditions, and if a word sounds doubtful to the operator he can pull the tape back for repetition or verify the word by glancing at the 35 perforations. The tape can be preserved as a check upon the operator who prepared the original perforated tape and upon the operator who transcribed the received message. It may also be used for re-transmission in another circuit.

In the local sounder circuit there is no 45 adjusting necessary. No time is lost by line interruptions and operators may be rated and paid according to their abilities, which are in no way affected by the qualifications of the operator at the other end of the line 50 as the impulses made by perforations are uniform. It will be seen, therefore, that this system has the capacity of three duplexed wires, and that there is no departure from the established style of working so far 55 as the operator is concerned. Messages may

be perforated by ordinary Morse key, auto-dot key or keyboard machine at any speed the operator is able to work, as he is entirely independent of the receiver.

Another important improvement is comprised in the novel form of contacts for the transmitter.

Another improvement relates to re-transmission, or repeating of messages from one circuit into another. This may be done very 60 effectually by utilizing the lever movements of a perforator to re-transmit into another circuit, impulses recorded by them on a tape and while the record is being made, so that perforation and re-transmission can be carried on at the same time, and whether drop copies are desired or not repetition may be 65 effected in this way from station to station over the longest circuits.

In the accompanying drawing: Figure 1 70 is a diagram illustrating transmission and reception according to this invention; Fig. 1^a, a diagram showing a local transcribing circuit including a reading sounder; Fig. 2, a diagram showing transmission, reception, 75 and relaying into another circuit.

Referring now to Fig. 1, T represents the automatic transmitter at the sending station X. If lever *l*, be pressed forward so that the rollers may grip the tape *t*, the 80 transmitting fingers *f*, will make contact through the cuts in the edges of tape *t*, meeting the lower contacts which are connected to positive and negative poles of battery *b*, respectively, thereby actuating polarized transmitter A, and sending dot and dash signals into line L, from main battery *b'*. At the receiving station Y, the line goes to polarized relay B, and thence to earth. This relay operates the perforator P through 85 battery *b*² which is connected to the switch *s*, and to the armature of the relay. An impulse beginning a character, dot or dash, moves the armature of B, to its contact *c*, closing the circuit of magnet *d*, and causing its lever to drive the punch through the tape, at the same time the lever reverses the position of switch *s* transferring the contact finger from segment *i* to *i'*, breaking the circuit of magnet *d*, and completing the circuit of magnet *e* in anticipation of the return of the armature of B to its original position against contact *c'*, whereupon magnet *e* is energized and its lever sends its punch 90 through the tape, and again reverses the 95. circuit of magnet *d*, and completing the circuit of magnet *e* in anticipation of the return of the armature of B to its original position against contact *c'*, whereupon magnet *e* is energized and its lever sends its punch 100 through the tape, and again reverses the 105 circuit of magnet *d*, and completing the circuit of magnet *e* in anticipation of the return of the armature of B to its original position against contact *c'*, whereupon magnet *e* is energized and its lever sends its punch 110 through the tape, and again reverses the

switch s , breaking the circuit at z' and restoring the circuit of magnet d . These two movements follow each other quickly and cuts are made in the tape almost in perpendicular lines, representing a dot, holes in the tape having a longer angle representing a dash.

It will be understood that the automatic transmitters only send dots, short impulses, 10 two for each character, and that the time and distance between the reversals of current of the polarized relay circuits determines the length of the characters, it being clear that the polarized relay armature having been moved to the left will keep the circuits in which are their armatures and left hand contacts closed until reversed by a hole in the upper edge of the tape passing between the contacts of the automatic transmitter.

The local transcribing circuit is disclosed in Fig. 1^a. The polarized relay C , operates, in this case, the sounder S from which the receiver operator copies the message. 25 It will be seen that the original tape is perforated by dot and dash movements of a Morse key; that the perforator magnets of P , are energized by dots only; that the automatic transmitter T , operates the polarized transmitter A , by dot impulses; that this polarized relay transmitter sends dot and dash impulses over the line to relay B , which operates the perforator P by dot impulses; that the tape produced operates 30 through transmitter Q the polarized relay C , by dot impulses; and that this relay operates the sounder by dot and dash impulses.

Fig. 2 represents simultaneous perforation and retransmission into another circuit 40 at Y . When the perforating levers of magnets e and d are attracted reverse impulses are transmitted from battery b to polarized relay h , as follows:—When receiving polarized relay v is energized by a negative impulse transmitted by perforation p' , its armature moves to contact c , magnet d , is energized, its punch driven through the tape, contacts g , n , closed and polarized relay h , energized. When armature of polarized relay reaches contact c^2 a positive impulse corresponding with perforation p , is sent into the line L , from positive pole of main battery BB . Simultaneous with these operations the switch s , has been moved 50 from contact i to contact i' , breaking the circuit of magnet d , and establishing a circuit for magnet e , which is energized upon the return of tongue of relay v , to its contact c' , when the punch of magnet e is 55 driven through the tape, contacts g' , n' closed and the circuit of polarized relay h reversed, sending a negative impulse corre-

sponding to perforation p' into line L from its contact c^3 . Transmission from X is the same as already described in Fig. 1.

I claim:

1. In telegraphy, an automatic transmitter, a local circuit, a polarized transmitter in said circuit controlled by the automatic transmitter, a main line into which signals are sent by said polarized transmitter, a receiving polarized relay in said main line, a local circuit controlled by said polarized relay, electromagnetic tape perforating means in said local circuit and 70 means controlled by said perforating means for sending into another line signal impulses corresponding with the actuations of the perforating means.

2. In telegraphy, a tape having perforations representing Morse characters, a transmitter controlled by said tape for operating a receiver in a main line, perforating means controlled by said receiver for perforating a tape in fac-simile of the original tape, and 85 means controlled by said perforating means for reproducing the signals perforated in the tape.

3. In telegraphy, a transmitter and a receiver in a main circuit, a perforator in a 90 local circuit controlled by said receiver, a tape perforated to represent Morse signals, and a polarized transmitter in a local circuit controlled by said perforator.

4. In telegraphy, a receiver, a perforator 95 controlled by said receiver, means controlled by said perforator for recording signals by perforations in a tape and means also controlled by said perforator for transmitting duplicate signals into another circuit simultaneously with perforation of said tape.

5. In telegraphy, an automatic transmitter, a local circuit, a polarized transmitter in said local circuit controlled by said automatic transmitter, means for actuating said 105 polarized transmitter by reverse impulses of uniform duration, a main circuit, a polarized receiver in said main circuit, means controlled by said polarized transmitter for sending impulses of unequal duration to said 110 polarized receiver, a local circuit controlled by said polarized receiver, a perforator in said local circuit, a local circuit controlled by said perforator, a polarized transmitter in said last named local circuit, and means 115 controlled by said last named polarized transmitter for sending impulses of unequal duration into another main circuit.

In testimony whereof, I have hereunto subscribed my name.

PATRICK B. DELANY.
